UNITED STATES PATENT OFFICE.

DAVID RUBIN, OF NEW YORK, N. Y.

WINDOW SCREEN.

Application filed October 13, 1927. Serial No. 226,008.

My invention relates to window screens of the extensible and collapsible type, and my purpose, generally speaking, is to provide a screen, specifically a full length screen, which 5 may be extended and collapsed both in length and width, whereby it may be adjusted to fit windows of various different sizes.

A window screen constructed in accordance with my invention is composed essential- 10 ly of four sections, two upper and two lower, or, in other words, an upper and lower left hand pair and an upper and lower right hand pair, the sections of each pair being slidably connected together so as to be extensible and 15 collapsible with respect to one another, and the two pairs being suitably connected together so as to be relatively extensible and collapsible in a direction at right angles to the direction in which the sections of the respec- 20 tive pairs are extensible and collapsible, whereby, as aforesaid, the screen is adjustable both in length and width so as to fit windows of various different sizes.

In a screen constructed as stated it is desir- 25 able that all of the sections be so connected together as to avoid the possibility of the sections bulging or springing with respect to one another in such manner as to permit spaces to exist between them through which flies or 30 other insects might pass, and accordingly it is my more specific purpose to so connect or interlock the sections that the possibility of same bulging, springing or spreading apart in such manner as to form openings which 35 would permit insects to pass through the screen is entirely avoided.

It also is my purpose to provide means of 40 an exceptionally simple, reliable and efficient nature to detachably secure a screen within a window.

Furthermore, it is my purpose to provide an extensible and collapsible screen of the type mentioned which is of simple, inexpensive construction, strong, durable, easy to adjust, and which is efficient in use.

With the foregoing and other purposes in view, my invention consists in the novel features of construction, combination and arrangement of parts as will be hereinafter 50 more fully described, illustrated in the accompanying drawings and defined in the appended claims.

In the drawings, wherein like characters

of reference denote corresponding parts in the different views:—

Fig. 1 is a front elevation of an extensible and collapsible screen embodying the novel and essential features of my invention;

Fig. 2, a section on an enlarged scale taken approximately on the line 2—2 of Fig. 1;

Fig. 3, a section on an enlarged scale taken approximately on the line 3—3 of Fig. 1;

Fig. 4, a perspective view showing the four sections of my screen separated from one another; and

Fig. 5, a detail perspective view showing my improved means for fastening a screen within a window.

By reference to the drawings it will be observed that my improved screen is composed 70 essentially of four screen sections, A, B, C and D, each consisting of a rectangular frame composed of an upper rail 10, a lower rail 12, an inner side rail 14 and an outer side rail 16, said rails preferably being formed from sheet 75 metal bent into U-shape in cross section and having the marginal portions of the respective screen elements 18 clamped therein.

The side rails 14, 16 of section A, the upper left hand section as shown in the drawings, have pressed therein or are otherwise suitably provided with outwardly directed, longitudinally extending dove-tailed grooves 20, 20, respectively, which slidably receive inwardly directed, longitudinally extending 85 tongues 22, 22, pressed from or otherwise suitably provided on the side rails 14, 16 of section B, the lower left hand section as shown in the drawings, whereby said sections A and B are connected together for relative collapsible and extensible adjustments.

The side rails 14, 16 of section C, the upper right hand section as shown in the drawings, have pressed therein or are otherwise suitably provided with outwardly directed, longitudinally extending dove-tailed grooves 24, 24, respectively, which slidably receive outwardly directed, longitudinally extending tongues 26, 26, respectively, pressed from or otherwise suitably provided on the side rails 100 14, 16 of section D, the lower right hand section as shown in the drawings, whereby these sections are connected together for relative collapsible and extensible adjustments in the same direction as the sections A and B.

The upper rail 10 of one of the upper

sections, specifically section C in the embodiment of my invention illustrated, is turned upon itself to provide, or is otherwise suitably provided with, a groove 28 which slidably receives the upper marginal edge portion of the upper rail of the other upper section, in this particular instance section A, while, in like manner, the lower rail 12 of one of the lower sections, in this instance section D, is turned upon itself to provide, or is otherwise suitably provided with, a groove 30 which slidably receives the lower marginal edge portion of the lower rail of the other lower section, specifically section B, 15 the pair of sections A, B overlapping the pair of sections C, D, whereby, as is apparent, the pair of sections A, B, are slidably connected with the pair of sections C, D for relative collapsible and extensible adjustments in a direction at right angles to the direction in which the sections of the respective pairs are adjustable with respect to one another. In other words, assuming that the tongue and groove connection between 20 the sections A, B and C, D provides for extension and collapse of the respective sections in a vertical direction, it is manifest that the sliding connections just described between the sections A, C and B, D provide for extension and collapse of the right and left hand pairs of sections with respect to each other in a lateral direction.

In order to interlock or so connect the left hand pair of sections A, B with the right hand pair of sections C, D as to prevent the sections of either pair from bulging or springing outward with respect to the sections of the other pair in such manner as might result in openings being produced between the respective pairs of sections through which flies or other insects might pass, I turn the upper rail 10 of one of the lower sections, in this instance section D, upon itself to provide, or otherwise suitably provide same with, a groove 32 which slidably receives the upper marginal edge portion of the upper rail 10 of the other lower section, specifically section B, the result being as aforesaid that the right and left hand pairs of sections are interlocked between the upper and lower ends of the screen considered in its entirety so that neither pair of sections can spring or bulge outwardly with respect to the other pair of sections.

By extending the tongues and grooves of both the right and left hand pairs of sections outwardly I am enabled to provide a sectional screen in which the respective pairs of sections lie closely adjacent to one another 60 in overlapped relation, the only space existing between the respective pairs of sections being the slight space necessary to accommodate the overturned portion of the upper rail 10 of section B which provides the groove 32. Thus it is apparent that I have

provided a screen which is adjustable both in length and width, in either direction irrespective of its adjustment in the other direction, and in which the respective sections in any adjustment thereof are so interlocked 70 as to prevent them from spreading apart in any manner which would produce an opening or openings through which insects might pass.

As a simple, inexpensive, easily applied 75 and easily manipulated means of detachably securing my improved screen in a window frame I provide the means illustrated in detail in Fig. 5 of the drawings, same consisting essentially of a screw eye 34 and a pin 36, the former being adapted to be fastened into the window frame and having the opening in its eye of elongated shape, and the latter being provided at one end with a head 38 and at its other end with a lateral 80 extension or extensions 40. A screen adapted to be secured in place by said screw eye and pin is provided in a rail thereof with an opening 42 sufficiently large to admit the extension or extensions 40 of pin 36, but 85 small enough to prevent the head of said pin from passing therethrough. The opening 42 is aligned with the opening in the screw-eye and the pin is passed through said opening 42 and the opening in said screw eye and then is rotated a quarter turn, the result being that the head of the pin engages the outer face of the screen rail and the lateral extension of the pin engages the rear 90 face of the screw eye thus detachably securing the screen to the window frame. Obviously, as many such securing devices as desired may be provided for any particular screen.

From the foregoing description considered in connection with the accompanying drawings it is believed the construction, operation and advantages of my improved collapsible and extensible screen will be fully understood. I desire to point out, however, 105 that various changes and desirable additions may be made in and to the structure shown within the spirit and scope of my invention as defined in the appended claims.

I claim:

1. In combination with a window screen including a frame having an opening therethrough, a screw eye adapted to be secured to a window frame, and a pin provided at one end with a head and at its other end with a lateral extension adapted to be passed through the opening in said frame and through said screw eye and rotated to secure the frame to said screw eye.

2. A window screen comprising two pairs 125 of sections arranged in superimposed relation; each section including an outer side rail, an outer end rail, an inner side rail and an inner end rail; means slidably connecting corresponding side rails of the two sec- 130

tions of each pair together, means slidably connecting the outer end rails of the sections of one pair with the outer end rails of the sections of the other pair, the inner end rail of the inner section of one pair being turned upon itself throughout substantially the full length thereof to provide a channel, and the inner end rail of the inner section of the other pair being slidably mounted in said channel.

3. A window screen comprising two pairs of sections arranged in superimposed relation; each section including an outer side rail, an outer end rail, an inner side rail and an inner end rail; means slidably connecting corresponding side rails of the two sections of each pair together, means slidably connecting the outer end rails of the sections of one pair with the outer end rails of the sections of the other pair, means forming a channel throughout substantially the full length of the inner end rail of the inner section of one pair, and means providing a tongue extending throughout substantially the full length of the inner end rail of the inner section of the other pair and slidably arranged within said channel to interlock

the inner end rails of the two inner sections together throughout the extent of overlap between said rails in any relative adjustment of the respective sections.

4. In a window screen, a pair of screen sections each inclusive of a frame composed of rails, at least one frame rail of each section being formed of a strip of sheet metal bent upon itself into U-shape to provide a channel to receive a marginal portion of the screen material of its related section, the said U-shaped sheet metal rail of one section being pressed after engagement of the marginal portion of its related screen material therein to provide a dovetailed groove serving to lock said screen material thereto, the said sheet metal rail of the other section being pressed after engagement of the marginal portion of its related screen material therein serving to lock said screen material thereto, said tongue being adapted to be engaged in said groove to slidably connect said rails together.

In testimony whereof I hereunto affix my signature.

DAVID RUBIN.
